CLAIM

The ornamental design for a packaging sheet for foodstuff, as shown and described.

DESCRIPTION

FIG. 1 is a front perspective view of a packaging sheet for foodstuff showing our new design according to a first embodiment;

FIG. 2 is a front view thereof;

FIG. 3 is a first side view thereof;

FIG. 4 is a rear view thereof;

FIG. 5 is a second side view thereof;

FIG. 6 is a top plan view thereof;

FIG. 7 is a bottom plan view thereof;

FIG. 8 is a front perspective view of a packaging sheet for foodstuff showing our new design according to a second embodiment;

FIG. 9 is a front view thereof;

FIG. 10 is a first side view thereof;

FIG. 11 is a rear view thereof;

FIG. 12 is a second side view thereof;

FIG. 13 is a top plan view thereof; and,

FIG. 14 is a bottom plan view thereof.

The broken lines in the figures illustrate portions of the packaging sheet for foodstuff that form no part of the claimed design.

1 Claim, 14 Drawing Sheets**Related U.S. Application Data**

having an international filing date of Oct. 19, 2018,
now Pat. No. Des. 902,709.
